United States Patent Office

Des. 202,142
Patented Aug. 31, 1965

202,142

MOTION PICTURE PROJECTOR

Raymond Herman, Brooklyn, N.Y., assignor to Richmond Research Corporation, Richmond Hill, N.Y., a corporation of New York

Filed Dec. 17, 1963, Ser. No. 77,829

Term of patent 14 years

(Cl. D61—1)

T 1 □ -3.

T 1 □ -4.

FIG. 1 is a side elevational view of a motion picture projector, showing my new design;

FIG. 2 is a front elevational view thereof;

FIG. 3 is a top plan view thereof;

FIG. 4 is a bottom plan view thereof;

FIG. 5 is a side elevational view thereof from the side opposite that shown in FIG. 1;

FIG. 6 is a rear elevational view thereof.

I claim:

The ornamental design for a motion picture projector, as shown.
